UNITED STATES PATENT OFFICE.

FRANK H. PARDON, OF OWENSBORO, KENTUCKY.

ROTARY ENGINE.

1,269,303.

Specification of Letters Patent. Patented June 11, 1918.

Application filed November 20, 1914. Serial No. 873,188.

To all whom it may concern:

Be it known that I, FRANK H. PARDON, a citizen of the United States, residing at Owensboro, in the county of Daviess and State of Kentucky, have invented a new and useful Rotary Engine, of which the following is a specification.

The present invention relates to improvements in rotary engines, one object of the present invention, being the provision of a construction of engine, in which the active portion of the rotor is eccentric to the carrying portion thereof and by means of which the same is adapted to coöperate with an oscillatory abutment that engages at all times the periphery of the eccentric portion of the rotor.

A further object of the present invention, is the provision of means for causing consonant action between the parts so that the abutment is properly positioned at all times for directing the exhaust pressure fluid away from the engine, while the pressure fluid is admitted for expansive force at the opposite side thereof.

A still further object of the present invention, is the provision of a novel form of balancing means, by means of which the active portion of the rotor may be properly balanced for high or low speed.

A still further object of the invention, is the provision of a rotary engine of exceedingly simple construction, and being composed of few parts the same is made more durable, efficient and practical in operation.

In the drawings—

Figure 1 is a longitudinal sectional view through the engine taken upon line 1—1 of Fig. 3.

Fig. 2 is a top plan view of the complete engine.

Fig. 3 is a section taken on line 3—3 of Fig. 1.

Fig. 4 is a perspective view of the eccentric strap and the connection with one of the abutments.

Fig. 5 is a perspective view of one of the adjustable weights.

Fig. 6 is a view similar to Fig. 3, of a modified form of abutment.

Figs. 7 and 8 are detail views of the abutment *per se*.

Referring to the drawings, the numeral 1 designates the chamber portion of the stator 55 which has attached thereto, the respective heads 2 and 3, having their respective shaft

carrying members 4 and 5. The shaft 6 is journaled in the heads as illustrated, and as here shown is provided with the two active members 8 and 9 spaced by the cylindrical portion 10 therebetween. The active members 8 and 9 are eccentric to the chamber of the stator and also to the portion 10, and are oppositely disposed to produce the desired balance effect.

Each active member 8 and 9 is recessed as at 11 and provided with the radial bar 12 which receives the slot 13 of the adjustable weight 14, the bar 15 and set screw 16 being provided to permit of the proper assembling of the weight 14 and the adjustment thereof relatively to the bar 12. It has been pointed out hereinbefore that the parts 8 and 9 of the rotor are oppositely disposed, to produce the desired balance effect. It is not possible to secure a perfect balance in this way, although an approximate balance may be obtained. A perfect balance, however, may be brought about by a proper shifting of the adjustable weights 14, radially of the rotor.

The pipe 17 is the fluid conducting pipe, such fluid being preferably steam, the same emptying into the by-pass 18, which is common to both nozzles or jets 19 so that the steam may be conducted to the respective active members 8 and 9 of the rotor at the angle as illustrated in Fig. 3.

There is formed in the stator 1 as illustrated in Fig. 3, one to each active member 90 of the rotor, a chamber 20, which is provided with the inlet 21 and with the exhaust pipe 22 leading therefrom. The blade 35 of the pivoted abutment 34 as will presently appear is mounted for sliding movement 95 through the port 21 to engage the periphery of its respective active portions 8 and 9 of the rotor and thus prevent steam after entering through the nozzle or jet 19 from passing to the left as shown in Fig. 3, so that the expansive force of the steam will be exerted upon the eccentrically disposed active member 8 or 9 to rotate the same in the direction of the arrow as indicated in Fig. 3, such pressure fluid being finally exhausted through the port 21, it being conducted thereto by the blade or abutment 35 when in the position as shown in Fig. 3. In Fig. 3 it will be understood that as the rotor turns, the exhaust steam is pocketed between 110 the periphery of the portions 8 or 9, upon the one hand, and the wall of the stator 1,

upon the other hand, the exhaust steam being carried around and delivered through the exhaust port 21.

An eccentric 23 is fixed upon opposite ends of the shaft 6 exteriorly of the journals 4 and 5, being secured fixedly thereto by means of the tapered pin 24. Surrounding the eccentric is the strap 25, there being interposed the antifrictional roller bearing 26 to reduce the friction therebetween. Each strap 25 is provided with the pitman 27, which is operably connected by the pin 28 to one end of the rocking arm 29. The opposite end of the rocking arm is connected to its respective rock shaft 30, which is journaled in the stud 31 and is anti-frictionally supported by the ball bearings 32, so that the shaft 30 will be operated with the least possible friction. Fixed upon the shaft 30 within the respective chambers 20 of the stator is the arm 34, which carries the abutment or blade 35 heretofore specified. It will thus be seen that as the shaft 6 is rotated, the blade 35 will be at all times maintained in contact with the periphery of its active member 8 or 9, and thus insure a steam tight joint at this point so that the exhaust steam will be properly directed into the port 21 and through the chamber 20 to the exhaust pipe 22. As there are two chambers 20, there are also two abutments 35 and two exhaust ports 21 and 22.

In order to provide a means for packing the face of the blade 35 nearer to the inlet port 19, there is disposed in the recess 36, a packing 37, which has disposed thereabove the block 38 made of a non-compressible material and acted upon by the set screw 39 from the top of the engine. Thus the packing 37 may be properly expanded to engage the curved face of the blade 35 so that the same will be packed during its oscillatory movement due to the periphery of the active rotors 8 or 9 and the action imparted thereto through the strap 25 and the eccentric 23.

A roller bearing 40 is journaled about the shaft 6 within the respective journal boxings 4 and 5, while mounted in the respective heads 2 and 3 of the stator, are ball bearings 41, there being led to each of the respective bearings through the ducts 43 and 44, the lubricant from the lubricating cup 42.

Although only two active members 8 and 9 are here illustrated, it is apparent that one, or any even number may be employed, in which event, each alternate active member will be operated either through its single shaft 30, where the alternate active surfaces are disposed in alignment, or where they are

disposed as quartering or at other various distances, any number of straps as 25 may be employed according to the number of active members and abutments 35 employed. 65

In the engine shown in Fig. 6, a chamber 45, having the inlet pipe 46 and the exhaust pipe 47 is disposed transversely of the stator 1'. Mounted for oscillation within the chamber 45, is a central abutment and valve 48, having the rotor engaging end or edge 49, and the pressure directing port 50. Thus steam will be directed through the port 50 to the left of the abutment 49, said member 48 being oscillated by the arm 29', operated similarly to the arm 29 to hold the abutment 49 in contact with the active portion 8' of the rotor which is similar to the rotor heretofore described, the pressure fluid exhausting through the curved portion 51 to 80 the pipe 47.

It will be noted that the cylindrical concentric portion of the rotor intermediate of the eccentric portions, forms a wall between the eccentric portions and thus prevent the steam from passing longitudinally of the rotor from one eccentric portion to the other. 85

It is also understood that any number of active members desired may be placed in the circumferential face of the concentric portion of the rotor. 90

What is claimed is:

A rotary engine comprising a stator having a bore and provided with eccentric chambers disposed on opposite sides of the bore, the stator having an inlet port and an outlet port for each chamber; a rotor journaled in the bore and provided with oppositely disposed eccentric portions moving in shifting contact with the peripheries of the respective chambers and tending to counterbalance each other approximately, the eccentric portions of the rotor having internal recesses which are oppositely disposed; weights in the recesses and shiftable radially of the rotor to effect an exact counterbalancing of the eccentric portions of the rotor; means for supporting the weights in adjusted positions in the recesses; and movable abutments in the chambers; between the inlet and outlet ports of the respective chambers, the abutments co-operating with the peripheries of the eccentric portions of the rotor. 100 105 110 115

In testimony that I claim the foregoing as my own, I have hereto affixed my signature in the presence of two witnesses.

FRANK H. PARDON.
